UNITED STATES PATENT OFFICE.

JAMES LEWIS TROUBRIDGE, OF LONDON, ENGLAND.

TOY MACHINE-GUN.

1,207,669.

Specification of Letters Patent. Patented Dec. 5, 1916.

Application filed April 5, 1916. Serial No. 89,026.

To all whom it may concern:

Be it known that I, JAMES LEWIS TROUBRIDGE, a subject of the King of England, residing at London, in England, have invented certain new and useful Improvements 5 in Toy Machine-Guns, of which the following is a specification.

This invention relates to toy-machine-guns and the object is to provide such a toy which 10 is capable of firing a large number of missiles in rapid succession in imitation of the well-known Hotchkiss or Maxim gun or guns of similar type.

In carrying out the invention I provide 15 a base fitted with a barrel and a suitably positioned magazine comprising a plurality of columns which hold the missiles in single file and a sliding carrier having missile holding or receiving slots or recesses corresponding 20 in number to the magazine columns said carrier conveying the missiles in turn from each of said magazine columns to the breech of the barrel. The said carrier is under the control of a crank handle or other actuating 25 device with which co-operates a cam or eccentric to produce the desired movements, and a further cam or tappets also co-operating with said crank handle control the actuation of a spring loaded striker the cam 30 and tappets being located in such relation that immediately after the carrier has conveyed a missile to the breech position the striker is operated to project such missile through the barrel.

35 Embodiments of the invention are illustrated in the accompanying drawings wherein—

Figure 1 is a side elevation of a toy-machine-gun constructed in accordance with 40 the invention and Fig. 2 is a rear elevation thereof; Fig. 3 is a partial perspective view of a second embodiment, and Fig. 4 a similar view of a modified form of magazine therefor and Fig. 5 a detail view of parts 45 shown in Fig. 3.

To refer firstly to Figs. 1 and 2 the gun 50 therein shown comprises a base *a* in which there is pivotally mounted at *a*¹ the barrel *b* together with the breech mechanism and firing devices, the former comprising a carrier *c* adapted to slide on a transverse plate *c*¹ and provided with two grooves *c*² each of which is in turn adapted to be brought into coincidence with the breech of the barrel, by 55 sliding movements imparted to said carrier in one direction by means of a double-armed

lever *d* *d*¹ fulcrumed at *d*² to the side of the breech body *d*³, one arm *d* of said lever extending through holes *c*³ in the plate *c*¹ and carrier *c* and the other arm *d*¹ being actuated by a cam *d*⁴ on a shaft *d*⁵ operated by a crank handle *d*⁶. Movement of the carrier in the other direction is produced by a spring *d*⁷ acting on the arm *d*¹ of the double lever.

The particular character of the movements 65 imparted to the carrier are immaterial so long as the missiles are collected from the magazine and conveyed successively to the breech, but in the construction illustrated Fig. 2 shows the normal position of the 70 carrier with the right hand groove *c*² in alignment with the breech, after which it is moved to the right with the grooves in coincidence with the discharge members of the magazine, then farther to the right to 75 bring the left hand groove *c*² to the breech and finally returned to normal position by the spring *d*⁷. The contour of the cam *d*⁴ provides for a pause in the movements of the carrier at the moments of firing and charging of the carrier. As regards the firing mechanism, there is also provided on the shaft *d*⁵ a double cam or tappet *e* adapted to act at correct intervals on the striker *e*¹ which is in the form of a bell-crank mounted 80 on a stud *e*² and under the action of a strong spring *e*³ coiled about said stud.

The magazine is formed with a wide upper receiving portion and as shown extends for the full width of a protecting screen *f*¹ 90 which may be provided. The lateral walls of the magazine are sloped inwardly at two parts at different angles, the upper part *f*² being substantially vertical, followed by an inclined intermediate part *f*³ and a lower 95 part *f*⁴ of much steeper inclination than the intermediate part. The space inclosed by the upper and intermediate wall portions constitutes a hopper *f* in which a large quantity of missiles *x* may be accommodated, such missiles being preferably cylindrical 100 in shape. The lower part of the magazine is divided into two channels *g* by means of a partition *g*¹ preferably extending somewhat above the angle between the intermediate and lower wall portions to facilitate guidance of the missiles into said channels, the inclined outer walls of which converge toward their lower ends to such an extent 105 that together with the partition *g*¹ the lower discharge orifice of each channel corresponds in width approximately to the diameter of

the missiles so that only one of the latter may be discharged at a time into a groove c^2 of the carrier c and thence to the breech as described.

- 5 The forward wall of the magazine may as shown be constituted by the protecting screen f^1 or by other suitable inclosing means according to the design of the gun adopted, and the rear wall by a plate, sheet 10 or equivalent h of any appropriate material it being contemplated to use a transparent or translucent substance such as glass or celluloid in order that the contents of the magazine can be seen from the rear for 15 facilitating the loading and more readily determining when the magazine requires recharging. The said rear wall may if desired be removable and retained in position by clips or equivalents h .
- 20 A training or elevating device for the barrel and connected parts may be provided shown as consisting of a slotted sector i extending from the base a , with a stud i^1 projecting from the breech-body d^3 through the 25 slot i^2 in the sector and secured in desired positions by a nut i^2 .

To now refer to the structure shown in Figs. 3 to 5 the magazine comprises two columns j j^1 each column having two walls 30 j^2 at right angles to a common third wall j^3 and the columns being of sufficient width and depth to allow the missiles to fall freely. An aperture j^4 is formed in the wall j^3 midway between the two columns 35 through which the missiles are ejected into the barrel k which is fixed to the base l in a corresponding position. The magazine is attached to the base l in a position to allow the sliding carrier m to move freely just 40 clear of the bases of the columns j j^1 . The said carrier m is provided with two slots m^1 m^2 of sufficient width to receive the missiles x as they fall from the magazine columns, and of a depth about equal to the 45 diameter of one of the missiles, the said slots being so placed that when the slot m^1 is at the base of the column j the other slot m^2 coincides with the aperture j^4 and vice versa when slot m^1 is opposite said aperture the 50 slot m^2 is at the base of column j^1 .

Two catches or arms n and n^1 are attached to the carrier m the latter passing through a slot n^2 in the base l and to guide the carrier there is provided at one end a rigid wire o which passes through a loop o^1 fixed to the base while at the other end the aforesaid arm n^1 operating in the slot n^2 effects this object.

An eccentric wheel or cam p and double cam or tappet p^1 fitted with a crank handle p^2 are rigidly fixed to a spindle p^3 having bearing in the base l and a striker q having arms q^1 q^2 and under the action of a coiled spring q^3 is mounted on the base l by loops 65 r in such a manner that the arm q^1 of said

striker is opposite the aperture j^4 and the other arm bears on the edge of the double tappet p^1 .

The magazine column j and j^1 need not necessarily be vertical but may be partly 70 vertical and partly inclined as shown in Fig. 4 the vertical part being constructed as above described and the inclined part constituted by two plates or the like s having raised flanges or ridges s^2 to serve as guides 75 for the missiles.

The operation of the gun just described is as follows: When the crank handle p^2 is rotated the double tappet p^1 presses downward on the arm q^2 of the striker and tensions the spring q^3 , thus cocking the striker while the eccentric wheel p by acting on the arm n moves the carrier m so that the slot m^1 containing a missile from column j reaches the breech aperture j^4 and the other 85 slot m^2 reaching the base of column j^1 receives a missile therefrom. At this point the double tappet p^1 releases its pressure on the striker arm q^2 and the other arm q^1 thereof under the action of spring q^3 strikes 90 the missile and projects it through the aperture j^4 and barrel k . On further rotating the crank handle p^2 the double tappet cocks the striker as before while the eccentric wheel p acting upon the arm n^1 moves the 95 carrier back so that the slot m^2 of said carrier containing the missile already received from column j^1 reaches the aperture j^4 and slot m^1 reaching the base receives a missile therefrom. The striker q is again released 100 and projects the missile in slot m^2 through the barrel, this operation being repeated as long as there are missiles in the magazine.

The gun may be fitted to a carriage, fort, motor-vehicle or the like or onto an aeroplane in which latter case the inclined magazine members r of Fig. 4 could serve 105 as the wings or planes thereof or parts of said wings or planes.

What I claim as my invention and desire 110 to secure by Letters Patent of the United States is: —

1. A toy machine-gun comprising in combination a barrel, a magazine positioned adjacent the breech of the barrel and having a 115 plurality of channels adapted to receive missiles in single file, a missile-carrier reciprocatable transversely to the axis of the barrel adapted to receive missiles from the magazine channels in turn and convey them 120 in turn to the breech of the barrel, means for reciprocating said carrier, and means for discharging the missiles through the barrel when brought into the breech position by the carrier aforesaid.

2. A toy machine-gun comprising in combination a barrel, a magazine positioned adjacent the breech of the barrel having a plurality of channels whose discharge apertures approximately correspond in width 125

carrier reciprocatable transversely to the axis of the barrel, having grooves adapted to receive missiles from the magazine channels in turn and convey said missiles in turn 5 to the breech of the barrel, means for reciprocating said carrier, a spring-loaded striker adapted to project the missiles through the barrel, and means for operating said striker in timed relation with the 10 movement of the missile carrier.

3. A toy machine-gun comprising in combination a base, a barrel supported thereby, a magazine positioned adjacent the breech of the barrel and having a plurality of channels 15 whose discharge apertures approximately correspond in width to the diameter of the missiles, a missile-carrier reciprocatable transversely to the axis of the barrel having grooves adapted to receive missiles 20 from the magazine channels in turn and convey them in turn to the breech of the barrel, a cam for reciprocating said carrier, a spring-loaded striker adapted to project the missiles through the barrel, a multiple 25 tappet for operating said striker in timed relation with the movement of the missile-carrier and means for manually actuating said cam and multiple tappet.

4. A toy machine-gun comprising in combination a barrel, a magazine positioned adjacent the breech of the barrel and having an upper portion constituting a hopper of considerable capacity the lateral walls of said magazine being each sloped at two 30 angles, the lowermost portion of considerably greater inclination than that preceding it, said lower portions being formed into a plurality of channels whose discharge aperture approximately corresponds in 35 width to the diameter of the missiles, a missile-carrier reciprocatable transversely to the axis of the barrel adapted to receive missiles from the magazine channels in turn and convey them in turn to the breech of the barrel, means for reciprocating said carrier, and means for discharging the missiles 40 through the barrel when brought into the breech position by the carrier aforesaid.

5. A toy machine-gun comprising in combination a base, a barrel supported thereby, a magazine positioned adjacent the breech of the barrel and having an upper portion constituting a hopper of considerable ca-

pacity the lateral walls of said magazine being each sloped at two angles, the lowermost portion of considerably greater inclination 55 than that preceding it, the lower portions being formed into a plurality of channels whose discharge aperture approximately corresponds in width to the diameter of the 60 missiles, a rear wall for the magazine formed of a transparent or translucent material, a missile-carrier reciprocatable transversely to the axis of the barrel having grooves 65 adapted to receive missiles from the magazine channels in turn and convey them in turn to the breech of the barrel, means for reciprocating said carrier, a spring-loaded striker adapted to project the missiles 70 through the barrel, and means for operating said striker in timed relation with the movement of the missile-carrier.

6. A toy machine-gun comprising in combination a base, a barrel supported thereby, a magazine positioned adjacent the breech 75 of the barrel and having an upper portion constituting a hopper of considerable capacity the lateral walls of said magazine being each sloped at two angles, the lowermost portion of considerably greater inclination 80 than that preceding it, said lower portions being formed into a plurality of channels whose discharge aperture approximately corresponds in width to the diameter of the 85 missiles, a front wall for said magazine constituted by a protective screen, a rear wall for the magazine formed of a transparent or translucent material, a missile-carrier reciprocatable transversely to the axis of the barrel having grooves adapted to 90 receive missiles from the magazine channels in turn and convey them in turn to the breech of the barrel, a cam for reciprocating said carrier, a spring-loaded striker adapted to project the missiles through the barrel, a multiple tappet for operating said 95 striker in timed relation with the movement of the missile-carrier and means for manually actuating said cam and multiple tappet.

In witness whereof I have signed this 100 specification in the presence of two witnesses.
